(57) **CLAIM**

The ornamental design for a gutter cleaner tool, as shown and described.

DESCRIPTION

FIG. 1 is perspective view of the gutter cleaner tool showing my new design, the handle is partially cut away for illustrative purposes, the broken line gutter is shown for illustrative purposes only and forms no part of the claimed invention;

FIG. 2 is perspective view of the gutter cleaner tool with the handle partially cut away for illustrative purposes;

FIG. 3 is a side view of the design, the opposite side being a mirror image;

FIG. 4 is a top view of the design with the handle partially cut away for illustrative purposes;

FIG. 5 is a side view of the design with the handle partially cut away, the opposite side being a mirror image;

FIG. 6 is a bottom view of the design with the handle partially cut away;

FIG. 7 is an end view of the design as seen from the left of FIG. 3; and,

FIG. 8 is another end view of the design as seen from the right of FIG. 3.
